His Attorney.

UNITED STATES PATENT OFFICE.

CHARLES M. AXFORD, OF CHICAGO, ILLINOIS, ASSIGNOR TO GENERAL ELECTRIC COMPANY, A CORPORATION OF NEW YORK.

ILLUMINATING APPARATUS.

1,171,917.

Specification of Letters Patent. Patented Feb. 15, 1916.

Application filed October 9, 1914. Serial No. 865,842.

To all whom it may concern:

Be it known that I, CHARLES M. AXFORD, a citizen of the United States, residing at Chicago, county of Cook, State of Illinois, 5 have invented certain new and useful Improvements in Illuminating Apparatus, of which the following is a specification.

My invention relates to illuminating apparatus, and more particularly to the 10 illumination of flags, banners and other display surfaces that shift with the wind.

It is my aim to provide automatically for the proper illumination of such display surfaces in spite of changes in the direction 15 of the wind without necessity for any but the occasional attention that would always be required by the particular light source employed in any particular case. Accordingly, I arrange the illuminating means for 20 throwing or projecting light upon the flag or the like adjacent its hoist or "staff" end in such a way that the same may turn with the flag when the wind shifts.

I have herein shown and described in detail 25 the best form of apparatus for the purpose of my invention at present known to me as specially adapted to the illumination of an ordinary flag or banner, but it will be understood that my invention is applicable 30 in connection with various sorts of display surfaces, and that it can be carried out and embodied in various forms of apparatus.

In the accompanying drawing, Figure 1 35 is a side view of a flag and the apparatus for illuminating it in accordance with my invention, one of the parts being in section; and Fig. 2 is a plan view.

The upright flag-staff shown comprises 40 a pole or mast 1 and a rod 2 secured in its upper end. The illuminating means 3 comprises a vertical trough-like reflector 4 having at its ends brackets 5 and 6 by which it is vertically pivoted so that when the wind shifts it may turn in proper relation 45 to the flag 7. As shown, the lower bracket 5 has a boss through which the rod 2 extends, and the upper bracket 6 has a similar boss through which extends a separate pivot pin 8 that carries the usual ornamental ball 50 9 and is secured in the upper end of the rod. In the present case the light source of the illuminating means 3 consists of a number of incandescent electric lamps 10 arranged in proper relation to the reflector 4.

As shown, these lamps 10 are mounted in 55 sockets 11 secured in the reflector 4, there being one set of lamps for lighting each side of the flag 7.

The circuit wires for the lamps 10 are arranged in conduits 12 on the back of the 60 reflector 4, and current is supplied them without interference with the turning of the reflector by means of contact rings 13 on the upper end of the mast 1 and brushes 14 on the bracket 5. It will be understood, 65 of course, that the form or curvature of the reflector 4 will in each particular case be chosen to give the most suitable distribution of the light on the surface of the flag, the particular form shown being merely 70 illustrative.

While various arrangements may be adopted, as shown the flag 7 is not arranged to be raised and lowered by halliards in the usual way, but is permanently secured to lugs 15 on the hubs of the brackets 5 and 6. While this mode of securing the flag 7 would in itself serve as a means for turning the reflector 4 with the flag when the wind shifts, I prefer not to rely on this 80 means alone, but to provide a vane 16 secured to the bracket 6 so as to turn the reflector with but independently of the flag. 75

What I claim as new and desire to secure by Letters Patent of the United States, is,— 85

1. The combination with a vertically flying flag, of means for projecting light upon said flag to illuminate it mounted at the staff end of the flag and turning with the same when the wind shifts. 90

2. The combination of a vertically flying flag, means for projecting light upon said flag to illuminate it vertically pivoted at the staff end thereof, and means for turning the illuminating means with the flag 95 when the wind shifts.

3. The combination of a vertically flying flag, means for projecting light upon said flag to illuminate it vertically pivoted at the staff end thereof, and means associated with 100 said illuminating means for turning the same with but independently of the flag when the wind shifts.

4. The combination of a vertically flying flag, means for illuminating said flag including a reflector vertically pivoted at the staff end thereof and electric lamps mounted and arranged in proper relation to said re- 105

flector, and vane means associated with said reflector for turning it in proper relation to the flag when the wind shifts.

5. The combination of a flag flying from an upright staff, means for illuminating said flag including a vertical trough reflector pivotally mounted coaxial with the staff and a plurality of electric lamps mounted in said reflector, means for supplying current to said lamps including stationary and movable contact means associated respec-

tively with the staff and the reflector, and vane means associated with said illuminating means for turning the same in proper relation to the flag when the wind shifts. 15

In witness whereof, I have hereunto set my hand this fourteenth day of September, 1914.

CHARLES M. AXFORD.
